UNITED STATES PATENT OFFICE.

GEORGE P. BRAND, OF NEW YORK, N. Y.

AUTOMATIC FLANGE-CONTROLLING MECHANISM.

1,180,105.

Specification of Letters Patent. Patented Apr. 18, 1916.

Application filed May 5, 1915. Serial No. 25,978.

To all whom it may concern:

Be it known that I, GEORGE P. BRAND, a citizen of the United States, residing at New York, in the county of New York and State of New York, have invented certain new and useful Improvements in Automatic Flange-Controlling Mechanism, of which the following is a specification.

This invention relates to certain new and useful improvements in flange controlling device for spools, particularly take-up spools for use in devices employing a movable sheet, such for instance as in automatic musical instruments.

15 The present invention has for its objects among others to provide improved means for controlling the spool flanges, operable to slowly bring the flanges up against the opposite edges of the sheet and to then retain the sheet as it is being wound and after it has been wound upon the spool.

In my construction the flanges are normally out of contact with the edges of the sheet as it is being wound upon the spool, 25 and are slowly brought together into contact with such edges, the construction being such that the flanges do not touch the edges of the sheet until after the latter has been given several turns or wrappings about the spool, 30 thereby presenting a plurality of layers of the sheet to offer sufficient resistance to the pressure of the flanges against such edges to prevent crushing or crumpling of such edges.

35 I provide a pneumatic with a valve control for automatically preventing undue pressure of the flanges against the edges of the sheet. No matter what width sheet is employed, the same pressure of the flanges 40 is obtained and the sheet forms the controlling element for controlling the pressure of the pneumatic, thereby causing the flanges to be controlled automatically for compensating for different widths of sheets. This 45 device may be used with any type of centralizing mechanism to deliver the music on the take-up spool between the flanges.

Other objects and advantages of the invention will hereinafter appear and the 50 novel features thereof will be particularly pointed out in the appended claims.

The invention is clearly illustrated in the accompanying drawings, which, with the numerals of reference marked thereon, form 55 a part of this specification, and in which Figure 1 is a front elevation of sufficient

parts of the instrument to show the application of my present invention, the flanges being in their separated position. Fig. 2 is a similar view showing the flanges against 60 the edges of the sheet. Fig. 3 is a vertical section from front to rear, as on the line 3—3 of Fig. 1 looking in the direction of the arrows. Fig. 4 is a bottom plan looking upward in the direction of the arrows on the line 4—4 in Fig. 1. Fig. 5 is an enlarged section through the pneumatic inflated and the valve closed. Fig. 6 is a similar view with the pneumatic deflated and the valve open.

Like numerals of reference indicate like parts throughout the different views.

Referring to the drawings, 1 designates the music spool box and 2 the take-up spool. The flanges 3 of the take-up spool are movable upon the shaft 4, being normally moved outward so as to be out of contact with the edges of the note sheet. The hub 5 of the flanges have grooves or the like 6 in which engage the upper forked ends 7 of the 75 arms 8.

9 is the shelf or bottom of the music spool box through vertical slots 10 in which pass the vertical arms 8, the said arms below the shelf being bent and extended horizontally, 85 as seen at 11, toward each other and they may or may not be disposed in grooves 12 in the under side of the shelf or bottom board 9. They are supported against downward movement by suitable means, as staples or the like 13 secured in the under side of the shelf 9. The inner ends of these members 11 are pivotally connected one to the end of a lever 14, as at 15, see Fig. 4, and the other, as at 16, to a point intermediate the ends of said lever 14, but between its fulcrum 17 and its other end to which is pivotally connected, as at 18, a rod or link 19 having at its other end a hook or any means 20 whereby it may be connected with and operated by the movable member of a pneumatic 21.

The pneumatic 21 has its fixed member 22 secured to some fixed part, as the end of the music spool box, as seen in Figs. 1 and 2, the movable member 23 being connected with and adapted to operate the rod 19, as seen in Figs. 1 and 2, as before described. A spring 24 of usual construction, as seen in Figs. 1 and 2, is employed upon the pneumatic to distend the pneumatic.

105 110 The mechanism above described may be employed either with or without a valve

upon the pneumatic. In the present instance I have chosen to show a valve 25 pivotally mounted, as at 26, at its lower end and its upper end movable toward and away from the movable number 23 of the pneumatic and acted upon by a spring 27 to keep it normally pressed in close contact with the movable member of the pneumatic. The tension of this spring is rendered adjustable by a screw 28, see Figs. 1, 2 and 3, whereby the tension of the spring upon the valve may be regulated as occasion may require. The valve 25 is constructed to control a port 29 in the movable member 23 of the pneumatic, as seen clearly in Fig. 5.

30 is a conduit or tube designed for connection with any source of exhaust of the player (not shown) and with the pneumatic 21 through the connection '31 and the bleed 32.

The movement of the valve 25 is slight, but I have shown it greatly exaggerated in Fig. 6, for the better understanding of the operation.

25 With the parts constructed and arranged substantially as hereinbefore described and with the flanges separated, as shown in Fig. 1, the pneumatic 21 being inflated and the spring 24 thereof acting to hold it inflated and to separate the flanges, the operation, as soon as tension is supplied and the motor started, is as follows: The take-up spool revolves and the music sheet 33 begins to be wound thereon. The pneumatic 21 starts to collapse through the restriction or bleed 32 and continues to collapse, slowly, carrying the flanges slowly toward each other and toward the sheet until the flanges come in contact with the opposite edges of the sheet, causing the pneumatic to halt and slightly opening the valve 25 and admitting air through the port 29 enough to overcome the bleed 32. This valve is caused to open more or less in accordance with the tension that is exerted in the operation of the exhaust to which the bleed connects, thereby always insuring a given pressure of the flanges against the edges of the note sheet, said pressure being of very light degree, which is in accordance with the tension of the spring 27 upon the valve 25. When once moved up in contact with the sheet, the flanges stay there as long as there is any tension in the player or as long as the player is being operated. When playing ceases, the spring 24 serves to distend the pneumatic which is inflated through the bleed 32 and the flanges are moved outward through the connections hereinbefore described.

60 Modifications in details may be resorted to without departing from the spirit of the invention or sacrificing any of its advantages.

What is claimed as new is:

65 1. A spool having movably mounted

flanges, a pneumatic having a bleed and connections for automatically moving the flanges slowly into contact with the edges of a note sheet.

2. A spool having movably mounted 70 flanges, a pneumatic having a bleed and connections for automatically moving the flanges slowly into contact with the edges of a note sheet and maintaining them in contact therewith. 75

3. A spool having movable flanges and automatic pneumatic flange-controlling means operable to hold the flanges from contact with the edges of a sheet during the preliminary winding thereof upon the spool. 80

4. A spool having movable flanges, pneumatic means and connections for moving the flanges toward the edges of a note sheet, and means for retarding the movement of said flanges to prevent contact with such 85 edges until a multiplicity of windings has taken place.

5. A spool having movable flanges, pneumatic means and connections for moving the flanges toward the edges of a note sheet, 90 means for retarding the movement of said flanges to prevent contact with such edges until a multiplicity of windings has taken place, and means for controlling the pressure of the flanges against the edges of the 95 sheet.

6. A spool having movable flanges, means operable to move them slowly into contact with the edges of a note sheet and means for holding them in contact with such 100 edges with constant pressure.

7. A spool having movable flanges, means for pneumatically automatically moving them toward the edges of a note sheet and means for limiting the degree of pressure of the flanges when in contact with such edges. 105

8. A spool having movable flanges, means for automatically moving them slowly toward the edges of a note sheet and 110 for maintaining them in contact therewith, and means for limiting the pressure of the flanges against such edges.

9. A spool having movable flanges, means for automatically moving them slowly toward the edges of a note sheet and 115 for maintaining them in contact therewith, and means for limiting the pressure of the flanges against such edges for preventing lateral movement of the sheet. 120

10. A spool having movable flanges, means for automatically moving them toward the edges of a note sheet and for maintaining them in contact therewith, and means for limiting the pressure of the flanges against such edges for preventing lateral movement of the sheet.

11. A spool having movable flanges, a pneumatic, connections between the same and the flanges and means operable in con-

junction with the pneumatic for limiting the pressure of the flanges against the edges of a note sheet.

12. A spool having movable flanges, operating means and connections for controlling the flanges, and means operable in conjunction with the operating means for limiting the pressure of the flanges against the edges of a note sheet.

10 13. A spool having movable flanges, operating means and connections for slowly controlling the flanges, and means operable in conjunction with the operating means for

limiting the pressure of the flanges against the edges of a note sheet. 15

14. A take-up spool with automatically controlled flanges, normally out of contact with the note sheet and means for automatically bringing them into contact with the sheet after a plurality of layers has been 20 wound upon said spool.

In testimony whereof I affix my signature.

GEORGE P. BRAND.
